(57) **CLAIM**

The ornamental design for a photographic lighting apparatus, as shown and described.

DESCRIPTION

FIG. 1 is a front isometric view of a first embodiment of the photographic lighting apparatus;

FIG. 2 is a rear isometric view thereof;

FIG. 3 is front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof;

FIG. 9 is a cross-sectional view taken along line 9-9 shown in FIG. 7;

FIG. 10 is a cross-sectional view taken along line 10-10 shown in FIG. 5;

FIG. 11 is a front isometric view of a second embodiment of the photographic lighting apparatus;

FIG. 12 is a rear isometric view thereof;

FIG. 13 is front view thereof;

FIG. 14 is a rear view thereof;

FIG. 15 is a left side view thereof;

FIG. 16 is a right side view thereof;

FIG. 17 is a top view thereof;

FIG. 18 is a bottom view thereof;

FIG. 19 is a cross-sectional view taken along line 19-19 shown in FIG. 17; and,

FIG. 20 is a cross-sectional view taken along line 20-20 shown in FIG. 15.

The broken lines in the drawings represent portions of the photographic lighting apparatus that form no part of the claimed design.

1 Claim, 20 Drawing Sheets
